REFRIGERATOR

James C. Rear, Berkeley, Calif., assignor to The
Union Ice Company, San Francisco, Calif., a
corporation of California

Application May 25, 1935, Serial No. 23,435

2 Claims. (Cl. 62—46)

My invention relates to means for enclosing a predetermined space, but with ready access thereto, in order to store articles which should be maintained at lower than normal atmospheric temperatures and at a standard humidity, together with a refrigerant means, such as ice, for maintaining the desired conditions.

An object of my invention is to provide a refrigerator of large ice and storage capacity, in which the rapidity of air circulation will be considerably more than customary.

Another object of my invention is to provide a refrigerator in which the rate of refrigeration is considerably accelerated over standard practice.

15 A further object of my invention is to provide means for insuring adequate air circulation within a refrigerator, despite adverse arrangement of materials stored therein.

20 A further object of my invention is to provide a refrigerator which is economical in its use of the refrigerant, such as ice.

25 An additional object of my invention is to provide an air forcing means for a refrigerator, which, although driven by a prime mover, does not add to the heat within the refrigerator.

The foregoing and other objects are attained in the embodiments of the invention illustrated in the drawings in which—

Fig. 1 is a front elevation of one form of refrigerator in accordance with my invention.

30 Fig. 2 is a cross-section the planes of which are indicated by the lines 2—2 of Fig. 1.

Fig. 3 is a cross-section the plane of which is indicated by the line 3—3 of Fig. 1.

35 Fig. 4 is a cross-section the plane of which is indicated by the line 4—4 of Fig. 3.

Fig. 5 is a cross-section on a vertical, longitudinal plane, of a display case refrigerator in accordance with my invention.

40 Fig. 6 is a cross-section the plane of which is indicated by the line 6—6 of Fig. 5.

Fig. 7 is a perspective view of a portion of an ice-supporting grid, some of the structure being shown in transverse cross-section.

45 Fig. 8 on the left half is a front elevation of a wall box type of refrigerator in accordance with my invention, and on the right half is a cross-section of such refrigerator on a vertical, transverse plane.

50 Fig. 9 is a plan of a walk-in refrigerator constructed in accordance with my invention.

Fig. 10 is a cross-section the plane of which is indicated by the line 10—10 of Fig. 9.

In its preferred form the refrigerator of my 55 invention includes an insulated enclosure which

is divided into a storage or food compartment and a refrigerant or ice compartment, in such a way that there is space for free circulation of air within the enclosure and between the two compartments, such circulation of air being augmented by mechanical blowing means having a driver therefor which is thermally insulated from the cooled enclosure. Preferably, the ice compartment is floored by a grid, not only affording a support for the ice but also providing ample air circulation passages communicating indirectly and directly with the ice and food compartments.

In the form of refrigerator of my invention especially shown in Figs. 1 to 4 inclusive, there is provided a cabinet 6 which is suitably mounted by casters 7, for instance, on the floor 8. The cabinet is preferably fabricated to include suitable thermal insulation 9, the exterior surface of which is preferably provided with an outer sheathing 11 and the interior surface of which is comparably sheathed by an interior lining 12. The structure so formed provides a pair of side walls 13 and 14, respectively, a top wall 16, and a floor 17. Likewise, the cabinet incorporates a back wall 18 and a front wall 19.

The enclosure so formed is preferably divided into a food chamber 21 and a refrigerant chamber 22, by means of a partition 23. The partition is preferably fabricated of wooden beams 24 and 26 which span the interior of the cabinet from the rear wall 18 to the front wall 19 and support inclined diaphragms 27 and 28 extending from the beams 24 and 26 to points adjacent the center of the cabinet, being spaced apart slightly to leave a passage 29 therebetween. Just above the opening 29, the front and rear walls of the cabinet are spanned by a center beam 31, which, together with the beams 24 and 26, is for the purpose of bearing the weight of the ice utilized as a refrigerant.

Extending between the beams 24 and 31, for instance, is a plurality of ice-supporting metal tubes 32, spaced apart to provide air passages 33 therebetween, and at their ends joined and maintained in appropriate relationship by straps 34 and 36 conveniently welded thereto. To each of the tubes 32 is fastened a pair of metal fins 37 and 38, each of which is of generally trapezoidal shape and is secured to its tube to depend therefrom in the general direction of, but spaced from, the diaphragm 27. The fins are somewhat shorter than the space between the beams 24 and 31, to allow ample air passage therebetween, and serve as good conductors of heat between air flow-

ing in the passages 33 and ice blocks 39 carried upon the tubes 32.

Spanning the beam 26 and the beam 31 is a similar ice-supporting means 40 for likewise upholding blocks of ice 41. The ice blocks are 5 preferably confined in a receptacle defined by upstanding lateral walls 42 and 43 which are spaced from the inner lining 12 of the side walls 13 and 14 in order to provide air passages 44 and 46 therebetween. The upstanding members 42 and 43 preferably are metal and are fastened to the beams 24 and 26 respectively. Included with such members in the receptacle are the inner surfaces of the beams 24 and 26, as well as of the 10 diaphragms 27 and 28, which are covered with metal sheaths 47 and 48, so that water melting from the ice blocks 39 and 41 falls gravitally over the tubes 32 and the fins 37 and 38 of both of the ice-supporting means, and finally drops gravitally 15 onto the metal linings 47 and 48. These are spaced from the lower termini of the fins to afford ample air passageways transversely thereof. The melted ice then flows through the aperture 29 into a drip trough 50 which is inclined downwardly toward the rear of the cabinet and connects with a drain 51 piercing the rear wall 18 and connected to waste.

In order that there may be a forced air flow over the blocks of ice in the ice chamber 22, I 30 preferably provide, adjacent the end of beam 31 and in registration with a passage 52 defined by the ends of the fins 37 and 38, an inlet aperture 53 piercing the front wall 54 of a duct generally designated 56, defining suitable air passages. 35 Axially aligned with the aperture 53 is a blower 57, preferably of the squirrel cage type, which discharges tangentially into the duct 56. The blower is mounted on a shaft with and is driven by a suitable electric motor 58 mounted on a shelf 59 in the rear wall 18. An insulating plate 61 extends 40 between the motor 58 and the blower 57, so that heat given out by the motor during operation of the fan will not be transferred to the interior of the storage cabinet. The motor 58 is likewise 45 exposed for cooling by passing external air currents.

A forced circulation is therefore effected of air drawn over the outer surfaces of the ice blocks and induced to flow therebetween and down 50 through the passages and between the ice-supporting tubes 32. Such air continues downwardly along the partition 23 to the central aperture 53, through which it flows for discharge peripherally by the blower 57 into the duct 56. The air advances along a continuation 63 of the duct and discharges at the bottom thereof through an aperture 64 adjacent the front, and through apertures 66 and 67 adjacent either side of the duct. Air so entering the food chamber 21 is evenly distributed 55 therein by vertically extending baffles 68 and 69, which extend almost to the underside of the partition 23 but terminate short thereof to provide circulation openings 71 and 72. The baffles 68 and 69 are preferably provided on their facing sides with angular supports, as at 73 and 74, to uphold shelves 76 for receiving material to be refrigerated, whereas on their external surfaces they are provided with brackets 77 and 78 which mate with comparable brackets 79 and 81, respectively, on the interior surfaces of the side walls 13 and 14, also for the reception of shelves to hold material to be stored. Access to the various subdivisions of the food chamber is had 60 through entrance doors 83 and 84, while access to the refrigerant chamber 22 is provided through

doors 86. On the front wall of the cabinet adjacent the doors 86 is an electric switch 87 and an indicating light 88, for controlling and showing the operation of the motor 58.

No matter how compactly materials may be 5 arranged within the food chambers of the refrigerator, the blower is effective, when driven, to compel the described flow of cool air from the aperture 53 down through the duct 56 and 63, out through the openings 64, 66, and 67, and into 10 the food chamber, wherein the air currents are distributed uniformly by the baffles 68 and 69. Exhausted and warmed air flows from the food compartments through the openings 71 and 72, and then through the passages 44 and 46, back 15 into the ice compartment, wherein such air, further coming into contact with the ice blocks 39 and 41, is cooled, properly humidified, and circulated over the ice-supporting and heat transferring means back into the aperture 53.

As shown especially in Figs. 5, 6, and 7, I have incorporated the refrigerator of my invention in a show-case especially for display purposes. This structure includes a cabinet 101 having a floor 102, a top wall 103, side walls 104 and 106, 25 a front wall 107, and a rear wall 108. These walls are all preferably fabricated of a central core 109 of thermal insulation which is exteriorly sheathed by a covering 110 of metal or comparable material and an interior sheath 111 of similar construction. Preferably, the front wall 107 is provided with an inclined portion 112 incorporating a pair of spaced panes of glass 113 and 114 which as so arranged are good thermal insulators but nevertheless permit a view of the interior of the enclosure. An electric light 116, within a mounting shield 117, enhances this feature. Access to the interior of the cabinet is 30 preferably attained by a pair of lower doors 118 and 119 and a pair of upper doors 121 and 122, 40 all cut in the rear wall 108.

Within, the cabinet is divided by a metal partition 123, extending from a point in abutment with the rear wall 108 to a point spaced from the front wall 107 to provide an air passage 124 45 therebetween, and extending laterally only so far as to afford openings 126 and 127 for the passage of air between the ends of the partition and the side walls 104 and 106 respectively. The space 128 above the partition 123 is designated as 50 a food storage compartment, whereas the space 129 therebelow is for the reception of a refrigerant, such as blocks of ice 131 and 132. The food compartment 128 is provided with food-supporting racks 133 and 134, each of which is 55 preferably of an open grid construction to facilitate the passage of air, and each of which is preferably carried on supports 136 and 137, spaced from the side walls 104 and 106 in order to provide air passages therebetween.

The ice compartment 129 includes means for supporting the ice. Spanning the interior of the cabinet between the front wall 107 and the rear wall 108 are beams 141 and 142 which are disposed symmetrically on each side of the center 65 of the cabinet, to provide support for inclined metallic drip trays 143, of which there are two, one located on each side of the center line. Superimposed on each of the drip pans 143 are identical grids 144. Each grid includes a plurality of inverted V-shaped metallic channels 146, which are retained in suitable spaced relationship by means of terminal straps 147 secured to the channels by welding, and at opposite ends turned over to provide footings 148. The chan- 70 75

nels 146, being spaced, provide air passages 149 therebetween, and, being short, provide at their outer extremities for the passage of air. Thus, air not only can circulate over the blocks of ice 131 and 132, but also can pass between and underneath the channels 146 and through the air passages 149, whereas melted ice can flow over such channels and down the drip pans 143 to a central channel 151 formed by the lining of the floor 102 and the beams 142. A float valve 152, disposed in a sump 153 connected to a drain 154, controls the outflow of excess melted ice to a suitable waste, not shown.

In accordance with my invention I preferably provide means for enforcing a circulation of air throughout the interior of the display cabinet refrigerator, even though the arrangement of materials on the shelves 133 and 134 may be adverse, in order that an acceleration of air flow over natural circulation and standard practice will be obtained, to utilize the refrigerant to the best advantage. For this reason the rear wall 108 is cut away to receive an inset metallic duct 156 which adjacent its upper end is pierced by an inlet aperture 157 leading to a squirrel cage type blower fan 158. The fan rotor is mounted on a shaft 159 of an electric motor 161 secured to a supplementary insulating plate 162 on the rear wall 108. The effect of this arrangement is to preclude motor heat from entering the cooled interior of the cabinet, although insuring a direct connection to the fan for enforcing a current of air to flow.

Air discharged from the fan 158 flows down through the duct 156 and from thence into a pair of nested ducts 163 and 164 extending to elongated outlet apertures 165 and 166 respectively. Air from the apertures discharges laterally and in opposite directions to flow forcibly into and between the lower ends of the inclined grid members 144. The ducts 163 and 164 not only assist in supporting the partition 123 but likewise serve as a baffle or separator for the major portion of the ice compartment 129.

In the operation of this arrangement, warm vitiated air is withdrawn from the food compartment 128 by the suction of the blower, into the aperture 157, and is forced by the blower to flow through the duct 156 and thence into the ducts 163 and 164. The air begins to be cooled at this point and discharges through the apertures 165 and 166 in opposite directions to flow slightly upwardly along the grids 144 and under and around the cakes of ice 131 and 132 resting thereon. The cooled and properly humidified air is then discharged through the passages 124, 126, and 127, being at least partially baffled by the partition 123. Such properly reconditioned air then rises over the racks 134 and through and over the racks 133, finally returning to the inlet aperture 157 of the blower, thus completing its circuit.

In a further modification of my invention exemplified by the wall box shown especially in Fig. 8, an insulated cabinet 181 is provided with an upper food storage compartment 182 and a lower ice storage compartment 183. These compartments are partially separated by a partition 184, and access to them is had by doors 186 and 187 respectively. The ice compartment is for the reception of a block of ice 188 resting upon a grid 189 of the previously described type. That is to say, the grid is made up of a plurality of inverted metal channels 191, so arranged and supported as to provide a plurality of air passages therebetween and thereunder. This grid is supported on

a drip pan 192 which in turn rests upon a beam 193 at one end and upon the floor of the cabinet at the other end. Drip from the melting block of ice 188 flows over the grid 189 into the drip pan 192 and thence to an outlet drain 194 connected to waste, in the customary fashion. 5

In order to accelerate the flow of air through the cabinet between the ice compartment 183 and the food compartment 182, I preferably build in the top wall 196 a transversely extending duct 197 which at its inlet is provided with an aperture 198 coaxial with a blower fan 199. An electric motor 201 situated on top of the cabinet drives the blower by a shaft 202 which passes through suitable insulation 203 so that heat from the motor is not transferred to the interior of the cabinet. 10 15

Air flowing upwardly in the food compartment 182 passes through the aperture 198 into the blower 199 and is discharged peripherally 20 thereby into the duct 197. This duct gives onto a vertical duct 204 built into the side wall of the cabinet and adjacent the bottom thereof transferring into an outlet duct 206. At its lower end the duct 206 is turned horizontally to 25 provide an outlet aperture 207 in substantial alignment with the grid 189, so that air discharged from the outlet 207 is induced to flow underneath the block of ice 188 in the spaces between and underneath the members of the 30 grid. The cooled and properly humidified air flows upwardly over the block of ice 188 to the compartment 182, through a passage 208 at one side of the partition 184 and through a passage 209 at the other side thereof, thus completing 35 the cycle at the entrance to the blower fan 199. 40

In relatively large installations it is preferable that an operator be permitted ingress thereinto, and for such purpose I disclose in Figs. 9 and 10 a so-called walk-in box. This box includes a 45 heavily insulated room 221 bounded by a floor 222, side walls 223 and 224, a rear wall 226, a front wall 227, and a top 228. All of these walls preferably are fabricated to include relatively heavy thermal insulating material. Within the room 221, to which access is had through an insulated door 229, are supports 231 for the reception of material to be maintained cool, such as the food products 232. 45

A plurality of superposed racks 233 is secured to the front wall 227 and is likewise supported by a nearly complete closure 234 which stops short of the floor 222 to provide an air discharge aperture 236. The racks 233 are each charged with a block of ice 237, and air is forced 50 to circulate over them by means of a blower 238 situated within the enclosure 234 and receiving air from within the room 221 through an aperture 239. The blower is driven by a shaft 241 extending through the insulation of the front 55 wall 227 and connected to an electric motor 242 mounted on a bracket 243. Heat from the motor, therefore, is not communicated to the interior of the room 221. Air is induced to flow into the blower 238, is discharged therefrom into the 60 space defined by the closure 234, and passes over the blocks of ice 237 on the racks 233. The cooled air discharges through the opening 236 into the room 221, and finally returns to the aperture 239, thereby completing its cycle. 70 75

I claim:

1. A refrigerator comprising a cabinet having an ice chamber therein, means forming a bottom boundary wall of said ice chamber, a plurality of spaced, inverted metallic channels form-

ing an ice-contacting supporting grid, means for affording air communication between one end of said grid and said ice chamber, and means for forcing air to flow into the other end of said grid and thence in contact with said grid and said boundary wall.

2. A refrigerator comprising a cabinet having an ice chamber therein, means forming a bottom boundary wall of said ice chamber, an ice-supporting grid including a number of spaced,

ice-contacting metal walls disposed at an angle to and close to said bottom boundary wall to form a number of lateral air passages extending for substantially the full length of said ice chamber but stopping short of the ends thereof 5 for affording communication with said ice chamber, and means for forcing a circulation of air through said air passages and said chamber.

JAMES C. REAR. 10
